UNITED STATES PATENT OFFICE.

ALFRED COLLIS, OF LONDON, ENGLAND.

ELEVATING-TRUCK, TRANSPORTER, OR THE LIKE.

1,295,698.

Specification of Letters Patent. Patented Feb. 25, 1919.

Application filed November 7, 1918. Serial No. 261,548.

To all whom it may concern:

Be it known that I, ALFRED COLLIS, a subject of the King of Great Britain, residing at London, England; have invented certain new and useful Improvements in Elevating-Trucks, Transporters, or the like, of which the following is a specification.

The object of this invention is to construct an elevating platform, truck, transporter or the like with jacks or similar lifting appliances actuated by a movement of the steering or a movable handle and the invention consists essentially of the combination of a frame carrying wheels, an elevating platform, jacks or similar lifting appliances connecting the frame or some part thereof or the wheel axles with the elevating platform, means connecting the jacks or similar lifting appliances with the steering 10 or movable handle for actuating the jacks for lifting or lifting and lowering and maintaining in position the elevating platform, and means for reversing the movement of the platform at the end of each 15 raising or lowering operation by a continuous movement of the operating handle.

The invention will be clearly understood from the following description aided by the annexed drawings in which—

30 Figure 1 is a side elevation and Fig. 2 a plan of a complete truck, transporter or the like.

Figs. 3, 4, 5 and 6 are sectional elevations of a jack or lifting appliance and its carrier or frame and part of the platform and showing the jack and platform in four positions from lowest to highest.

Fig. 7 is a sectional plan of the frame carrying a jack and its operating mechanism.

40 A frame 1 is mounted on wheels 2, 2, which are in a fixed position, and also on one or two steering wheels 3 located at the front of the improved device. The frame 1 is also provided with and has secured thereto four vertical frames 4 for receiving a corresponding number of lifting jacks which will be hereinafter more fully explained, there being two frames, and four 45 jacks on each side of the frame 1.

An elevating platform 6 is mounted over the frame 1 and constructed with four depending posts 7 which fit the vertical frames 4, said posts 7 having ratchet teeth 8 on 55 one edge.

Each jack mechanism is constructed with a bell crank lever 9 journaled to the frame

4 on an axle 10, the latter also carrying a spring controlled pawl 11 the nose of which engages the teeth 8 of the adjacent depending post 7. To the lower arm 12 of the bell crank 9 I pivot a second pawl 13 which also engages the teeth 8 of the depending post 7. On the axle 10 carrying the spring controlled pawl 11 is a rocking lever 14 one end of which is engaged by pin 15 actuated by a spring 16; the other end of the lever 14 is provided with a recess 17 and sloping edges 18, 18^a.

The end of the lever 14 acted upon by the 70 spring controlled pin 15 is made somewhat W shape and the pin 15 acts against this end so that when the lever 14 is swung on the axle 10 it will be held in either of two positions in which it is placed and its movement 75 completed.

I provide on the platform 6 for each jack mechanism a depending post 19 having two lugs 20, 21 or equivalent means which engage a pin 22 on the rocking lever 14 to actuate 80 the said lever just before the end of either raising or lowering operation of the platform.

The sloping portion 18 on the end of the lever 14 engages a pin 23 on the pawl 11 85 and the recess 17 engages a pin 24 on the other pawl 13 connected to the bell crank lever 9.

The two bell cranks on each side are connected by a rod 25, both rods being extended toward the steering post 26 and positioned in proximity to the handle 27 and in line with fixed jaws 28 thereon, the steering and pulling handle being pivoted to the axle 32 of the steering wheel 3.

The rods 25 are connected at one end by a cross bar 29 and are controlled in their movement by a spring 30 engaging the said cross bar and the frame 1.

The handle is free to move the truck about 100 with the platform in any position.

Assuming the platform to be lowered and the parts in the position shown in Fig. 3 the handle 27 is raised and in so doing the jaws 28 will engage the ends 31 of the rods 25 and push the rods longitudinally and thereby actuate the bell cranks 9 and lift the pawls 13 one tooth, the other pawls 11 riding into the teeth below the one they have engaged to hold the racks, see Fig. 4, the movement of the rods 25 putting tension on the spring 30. On a reverse movement of the handle the spring 30 will bring the rods 25 back and also the bell crank levers 9 for their

pawls 13 to engage the next lower tooth in the racks 7 and by a continued reciprocating movement of the handle the jacks will be lifted and when the platform 6 has been 5 raised the desired height the bottom lugs 21 on the depending posts 19 will have engaged the pins 22 of the rocking levers 14 on the bell crank axles 10 and moved them over and as soon as the pins 15 have passed the highest 10 point 33 the springs 16 will act upon the pins 15 and cause them to move the rocking levers 14 over by engaging the sloping portion until the end is nearly reached and the sloping portions 18 come against the pins 23 on 15 the pawls 11, the weight of the platform 6 and load holding the pawls 11 in engagement with the racks 7 against the pressure of the springs 16 on the pins 15 see Fig. 5, and the recesses 17 in the levers 14 will engage the 20 pins 24 on the pawls 13 pivoted to the bell crank levers, the platform being held by the pawls 11 in the raised position.

To lower the platform the handle is pushed fully back and its jaws or yoke will engage 25 the ends of the distancing rods and move the bell crank levers over and the pawls 13 being free from the recess 17 will by the action of their springs engage a tooth and slightly lift the racks 7 releasing the pressure of the 30 platform and load on the pawls 11 and allow the pins 15 to complete their movement to the end of the slope 33 of the rocking lever 14 and thus to move these levers 14, and the sloping surfaces 18 engaging the pins 23 will 35 then move the pawls 11 away from their teeth, the springs 16 on the pins 15 being stronger and will overcome the tension of the springs of the pawls 11 and allow the platform to be lowered by the pawls 13. When 40 the platform is lowered one tooth the pins 24 on the pawls 13 will come against the sloping portions 18^a of the rocking levers 14 and press same downward and be forced along same into the recesses 17 and out of engagement with their teeth in the racks 7 at the 45 same time owing to the noses of the rocking levers 14 being pressed downward the sloping surfaces 18 will be moved away from the pins 23 on the pawls 11 and allow the pawls 50 11 under action of their springs to engage with teeth in the racks 7 and hold same for a repeat operation of the pawls 13 and by a continued reciprocal movement of the handle the platform will be lowered and just as 55 the lowering is reaching its limit other stops 20 on the posts will push the rocking levers over and the spring pins 15 will pass over the point 33 and act on the other slope and will place them in the opposite position and clear 60 of the pawls, the platform resting on the two pawls see Fig. 7 or on the frame.

The rods 25 between the jacks mechanism are positioned to insure that all pawls move

in register to provide equal movement to actuate the platform in a proper manner.

What I do claim as my invention, and desire to secure by Letters Patent, is:—

1. An elevating truck of the class specified comprising a frame having wheels, a part of the wheels being used as steering means therefor, a rising and lowering platform on the said frame, jack mechanism arranged in pairs at opposite sides of the frame and each provided with a toothed post, the jack mechanism connecting the frame and the platform, bell crank levers carrying pawls operative to raise and check the movement of the posts, a longitudinally shiftable rod connected to the jack mechanism on each side of the frame through the bell crank levers, rock levers closely associated with the bell crank levers for releasing the pawls relatively to the posts, holding means engaging the said rock levers, a handle mounted at the forward portion of the truck and having devices for engaging the forward ends of the rods for actuating the jacks and causing the platform to rise and lower, and means extending downwardly from the platform for operating the rock levers to cause the latter to perform their function.

2. An elevating truck of the class specified comprising a frame having wheels, a part of the wheels being used as steering means therefor, a rising and lowering platform on the said frame, jack mechanism arranged in pairs at opposite sides of the frame and each provided with a toothed post, the jack mechanism connecting the frame and the platform, bell crank levers carrying pawls operative to raise and check the movement of the posts, a longitudinally shiftable rod connected to the jack mechanism on each side of the frame through the bell crank levers, rock levers closely associated with the bell crank levers for releasing the pawls relatively to the posts, holding means engaging the said rock levers, a handle mounted at the forward portion of the truck and having devices for engaging the forward ends of the rods for actuating the jacks and causing the platform to rise and lower, the rock levers having projections, and posts depending from the platform and independent of the said toothed posts of the jack mechanism and provided with projections to engage a part of the rock levers to shift the latter and cause them to coöperate with the pawls.

In testimony whereof I have hereunto set my hand in presence of two subscribing witnesses.

ALFRED COLLIS.
